UNITED STATES PATENT OFFICE.

EDWARD P. CRESSLER, OF NEWTON, KANSAS, ASSIGNOR OF ONE-HALF TO JOHN L. GROVE, OF NEWTON, KANSAS.

CLEANING BRUSH.

Application filed April 29, 1928. Serial No. 105,444.

This invention relates to cleaning brushes and, more particularly, to brushes which are used for removing deposits of foreign matter from the teeth.

5 The ordinary bristle toothbrush, being too costly to warrant the use of a new brush for each cleaning of the teeth, is commonly used a great many times and, consequently, acts as a collector of disease germs, thus promoting 10 rather than preventing diseased conditions in the mouth by each application of the brush subsequent to the first use thereof.

It has been proposed to overcome, in a measure, certain of these objectionable features by the provision of a tooth-cleaning and massaging brush wherein the brush-head, or at least the bristles thereof, are constructed wholly of soft rubber. Such a brush, however, having its bristles constructed of soft 20 rubber, lacks the necessary rigidity or stiffness for entering the interproximal spaces of the teeth in the cleaning operation, and its bristles bend over, which results in a mopping or massaging of the more exposed portions only of the teeth, rather than the thorough brushing and cleaning of the entire exposed portions of the teeth and of the spaces therebetween which is desired.

I have discovered, and the present invention is predicated upon the discovery, that by constructing the brush of paper or similar fibrous material, any desired degree of stiffness of the material may be obtained and a much finer tongue or bristle, which will yet be harder and firmer than rubber, may be produced. By then coating the brush—or the prepared material prior to the formation of the brush—with latex, or any other substance having substantially the same properties, all sharp edges which might have a tendency to cut the gum are covered and the support and flexibility of the latex, rubber, or other waterproofing compound, imparted to the brush parts serve to prevent the bristles 40 from bending over or breaking in use.

It may now be stated that an object of this invention is the provision of a cleaning brush comprising a pair of detachably associated elements wherein one of the elements, the 50 brush-head or cleaning element, is cheap enough of construction to warrant use thereof but once, whereby it may be thrown away after such use and another similar element substituted for subsequent use.

55 Another object of the invention is the pro-

vision of a cleaning-brush wherein the brush-head, or at least the bristles or tongues thereof, are constructed largely of paper or the like material.

A further object of the invention is the provision of a cleaning-brush wherein the bristles are constructed of paper or the like material coated with latex or some similar vulcanizable coating.

With these and other objects in view, as will 60 become apparent as the description proceeds, the invention consists of the novel features of construction, combinations of elements, and arrangements of parts hereinafter to be fully described and pointed out in the claims.

A full and complete understanding of the invention may be obtained from a consideration of the following detailed description, taken in connection with the accompanying drawings forming a part of the disclosure, it 70 being understood that, while the drawings show certain practical embodiments of the invention which have proven satisfactory in use, the latter is not to be confined to the showing thereof but may be changed or modified 80 so long as such changes and modifications mark no material departure from the salient features of the invention as hereinafter fully described and claimed.

85 In these drawings:

Figure 1 is a view in perspective of a cleaning-brush embodying certain features of my inventive-concept;

Figure 2 is a fragmentary enlarged view in plan of a strip from which the head of a brush 90 as shown in Fig. 1 is constructed;

Figure 3 is a similar view of a modified form of brush-forming strip;

Figure 4 is a sectional view, taken on the line 4—4 of Fig. 3;

Figure 5 is an enlarged fragmentary view in plan of still another form of strip;

Figure 6 is an enlarged fragmentary view in side elevation illustrating one form of handle and the manner in which it is associated 100 with the brush-head;

Figure 7 is a fragmentary view in plan of the form of handle shown in Fig. 6;

Figure 8 is a similar view of the form of handle shown in Fig. 1;

Figure 9 is an enlarged sectional view, taken on the line 9—9 of Fig. 6;

Figures 10 and 11 are views in end elevation illustrating the manner in which the brush-head is bored or drilled to accommodate the 110

forms of handle shown in Figs. 7 and 8, respectively; and

Figures 12 and 13 are enlarged detail sectional views, illustrating the location of the 5 latex coating when the strip is dipped and when the brush-head, as a whole, is dipped, respectively.

Referring, now, to the particular embodiments of the invention illustrated in the accompanying drawings, the reference-character 1 designates a cleaning-brush in its entirety. Preferably and as shown, this brush 10 comprises a handle 2 and a body-portion or brush-head 3 detachably associated therewith in order that after the brush has once been 15 used, the head or brush proper may readily be removed and another head substituted therefor for subsequent use.

The brush-head 3 may be constructed in 20 a variety of ways (three being shown in the drawings for illustrative purposes), it being necessary only that the bristle or tongue portions 4 of the brush-head be constructed of paper or any equivalent cheap material having 25 the required characteristics, and be coated with latex or any equivalent coating compound, as shown at L in Figs. 12 and 13, to insure the desired advantageous results.

For instance, the brush-head may be 30 formed by winding a strip 5 (Fig. 2) of paper or similar material which has previously been serrated along one entire edge to provide the bristles or tongues 4, upon itself and securing the adjacent layers 6 to each other by a suitable adhesive. The strip 5 may be coated 35 with latex or other waterproofing substance prior to the winding thereof into brush form, or the entire brush-head, when wound, may be dipped in the coating solution, in which 40 event, the coating solution itself acts as an adhesive and holds the layers together. In this form, the bristles or tongues 4 of adjacent layers are quite close together and a 45 relatively compact, stiff brush-head is produced.

It is preferable, however, that the bristles or tongues of adjacent layers 6 be spaced 50 from each other both to permit more ready individual movement of the bristles and to provide space within the brush for the reception 55 of a dentifrice such as is usually employed and applied with the brush. This result may be obtained by winding a spacing strip 7 with the strip 5. The strip 7 may be of any desired thickness, it is preferably slightly less than half the width of the strip 5, and may be adhesively secured thereto prior to the winding and coating operations.

The same result may be obtained by employing a strip 8 (Fig. 5) which is provided 60 with tongues 9 extending from one side thereof throughout portions only of its length, the intermediate portions 10 serving to space the tongue-bearing portions 11 from each other 65 when the strip is wound into brush form.

The portions 10 and 11 of the strip 8 are, of course, made progressively longer from the end of the strip which is to be located centrally of the brush in order that each portion may be of the desired length.

In Figs. 1 and 8, I have illustrated one form of handle which may be advantageously employed, and wherein an end 12 thereof is bifurcated to provide a pair of diverging, tapered tongues 13 which are designed to be 75 inserted with some small degree of force into similarly shaped holes 14 extending inwardly from an end of a brush-head 3 constructed in accordance with any of the above-described embodiments. The tongues 13 and 80 holes 14 may be of any desired shape in cross-section, but it is desirable that they be tapered in order that the handle and brush-head may remain firmly assembled during use of the brush and yet be readily separable for changing 85 brush-heads.

The form of handle illustrated in Figs. 6, 7 and 9 is provided at one of its ends with a single tapered tongue 15, designed to fit within a similarly shaped hole 16' extending 90 inwardly from an end of the brush-head 3, and a flat holding strip 16 spaced from the tongue 15 and adapted to bear against the back of the brush-head 3, the free end of the strip 16 being bent toward the tongue 15, as 95 at 17, to engage with the brush-head to prevent relative longitudinal movement of the elements. The brush-handle 2 may be made of any suitable material and the hole 16' or holes 14, as the case may be, are preferably 100 swabbed with latex in order to cause a greater gripping action between the brush-head and handle.

With any cleaning toothbrush, it is essential that the bristles be small and firm enough 105 to pass between or even into the interproximal spaces of the teeth so as to get a sweeping effect in the cleaning action. By constructing the brush of paper, it is not only possible to obtain a much finer and firmer 110 bristle than is possible with rubber, felt or string, but the bristles, even should they become broken and detached—which is unlikely 115 from a single use of the brush—will readily decompose in the body and therefore do no 120 harm.

By coating the brush-head, or at least the bristles thereof, with latex, the bristles are less liable to break off and the possibility of cutting of the gums by the edges of the paper 125 is obviated.

By the term "latex" I mean to define any compound including in its composition a latex such, for instance, as the latex of the rubber tree combined with other elements and prepared in such a way that the compound when applied in liquid form to an object will harden thereon and constitute a flexible, impervious, rubber-like coating. This coating 130 is capable of being vulcanized, or of being

subjected to heat without vulcanization and without material change in its physical characteristics.

I may also use any equivalent coating composed of a pound which is water-proof and which when applied to an object in liquid form will harden to constitute a flexible, impervious, rubber-like coating capable of withstanding vulcanizing temperature without material change in its physical characteristics.

A brush-head constructed as above specified is a complete and usable article without vulcanization of the coating and may be marketed in that condition, or it may be originally sterilized by application of heat thereto, resulting in vulcanization of the coating before it is marketed. In any event, such a brush-head may be sterilized by any of the methods known to surgeons either before or after sale without damage thereto.

What I claim is:

1. A toothbrush body including a strip of fibrous material wound upon itself, integral cleaning tongues extending from portions of the edge of the strip, and a flexible impervious coating on said cleaning tongues.

2. A cleaning-brush body including a narrow strip of fibrous material wound upon it-

self and formed with integral cleaning tongues extending from one edge of the strip, and a flexible impervious coating possessing adhesive properties on the strip retaining it in wound condition and covering the tongues.

3. A cleaning-brush body including a narrow strip of fibrous material having a plurality of spaced groups of integral cleaning tongues extending from one edge thereof and wound upon itself so that portions of the strip without tongues space the groups of tongues from each other, and a flexible impervious coating on said cleaning tongues.

4. A toothbrush including a brush-body and a handle detachably associated therewith, said body being constructed wholly of a strip of fibrous material formed with integral cleaning tongues, coated over its entire surface with a flexible impervious coating possessing adhesive properties, wound upon itself and retained in wound condition by said coating.

5. A brush-head having cleaning tongues formed of fibrous material and having a rubber coating.

In testimony whereof, I have affixed my signature hereto.

EDWARD P. CRESSLER.
